UNLOADING MECHANISM

Filed Dec. 31, 1923

Fig. 1

UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

UNLOADING MECHANISM

Application filed December 31, 1923. Serial No. 683,612.

This invention relates generally to fluid exhausting means, and more particularly to means for unloading vacuum pumps when a certain vacuum has been reached.

5 An object of the invention is to provide an improved unloading mechanism for a vacuum pump. Another object is to provide an automatic means for unloading the vacuum pump when a predetermined low pressure has 10 been reached thereby making it possible to maintain a constant vacuum. A further object is to provide an improved means for controlling the unloading mechanism. A still further object is to provide improved means 15 whereby the atmospheric pressure will be sufficient to actuate pump valves for unloading purposes.

In the accompanying drawings I have shown for purposes of illustration one form 20 which my invention may assume in practice.

In these drawings,—

Fig. 1 is a side elevation partly broken away to show the valve mechanism of the pump.

Fig. 2 is an enlarged vertical sectional de- 25 tail of the means for controlling the unloading mechanism.

In the illustrated embodiment of my invention I have shown my improved unloading means in connection with a usual vacuum 30 pump 1 having a reciprocable piston 2 and inlet valves 3 which allow communication with the usual chamber 4 and the cylinder of the pump while a tank 5 has communication with the chamber 4 as by a pipe 6. It will of 35 course be understood that any type of compressor might be used and that the valves 3 might only be relief valves. The means for unseating the valves 3 is of standard construction, one being used for each valve, and com- 40 prises a downwardly projecting casing 7 having a reciprocable piston mounted therein with an upwardly projecting stem 7'. This construction is of a well-known form and it will suffice to say that when the rod 7' is

45 forced upwardly against the bottom of the valve, it will hold the same open. The bottom of the cylinder of each mechanism communicates with the other as by a pipe 8 which in turn has communication with a pipe 9 leading to the controlling means 10 which in turn

has communication with the tank 5 as by a pipe 11.

The controlling means shown in Fig. 2 controls fluid below atmospheric pressure. This means, briefly described, comprises a body portion 12 having a chamber 13 therein which communicates with the tank 5 as by pipe 11. Actuation of the controlling means is brought about by means of a diaphragm 14 disposed on the upper surface of the body 12 and covering the chamber 13. It is held in position as by a cover 15 which has an upwardly extending guide portion 16, this cover being held to the body 12 by bolts or other suitable means. A stem 17 fixed to the diaphragm projects upwardly through guide 16 while a spring 18 which surrounds the stem and guide tends to force the stem 17 in an upward direction as by having engagement with a nut and washer 19 adjustably screw threaded on the upper end of the stem 17. It will be noted that the cover 15 forms a chamber 20 disposed above the chamber 13 and has communication with the atmosphere as by a port 21. The remaining portion of the controlling means comprises a valve supporting member 27 which supports a vertically movable control valve 22 having ports 23 communicating with a bore 28 and adapted to engage a movable plate 24 disposed in a connection 31. This plate has ports 25, and a spring 26 mounted in a bore 30 of member 31 maintains the plate in engagement with the end of the valve 22 or the lower surface of the valve supporting member 27. In the position as shown, the bore 28 is closed at its lower end by the plate 24 and the chamber 30 has communication with the atmosphere as by the ports 25 and passages 32 within the member 27. A recess 33 is also formed in the lower end of the member 27 for allowing communication between chambers 13 and 30 when the valve 22 is in its uppermost position.

The operation of the device is substantially as follows. Assuming that the pressure in the tank 5 is not down to the predetermined low pressure, the valves 3 will continue to operate normally. Pressure in the chamber 13 of the controlling means 10 will always correspond to that in the tank due to the

connection 11. When the tank pressure has reached a predetermined low point, the pressure of the atmosphere, which has communication with the chamber 20 as by port 21, will be greater than the resisting pressure in the chamber 13 and that of the spring 18, and hence will force the diaphragm 14 downwardly against the upper end of the valve 22 thereby forcing the latter also downwardly so that the lower end thereof will abut against the plate 24 as shown in Fig. 2, thus closing the lower end of the bore 28, it being noted that the ports 25 are disposed on the outside of the valve member 22. It will be noted in this position that atmosphere communicates with chamber 30 as by ports 32 and 25. The pipe 9 is connected to the lower end of the connection 31 so that atmospheric pressure will be transmitted to the pipe 8 and thence to the lower side of the pistons within the cylinders from which the piston rods 7' project. The atmospheric pressure on the lower side of the piston being greater than the pressure within the chamber 4 will raise the piston rod 7' against the lower end of the valve and hold it open. When the pressure in the tank rises above the predetermined low point, the pressure of spring 18 and the tank pressure in the chamber 13 will force the stem 17 upwardly while springs 26 and 26' will also force the valve 22 upwardly so that the plate 24 will rest against the lower surface of the member 27 and thereby close the lower end of the passages 32. Communication between the tank and the pipes 8 will then be reestablished as by pipe 11, ports 23, bore 28, ports 25 and chamber 30, thus cutting off atmospheric pressure on the under side of the piston rods 7'. The pressure on the pistons in the cylinders 7 is now such that they will be retracted from engagement with the valves, thereby letting the latter resume their normal operation.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a vacuum pump and means for automatically unloading said pump when a predetermined pressure below atmospheric is reached, said unloading means including a fluid actuated unloading element and a pilot valve controlling the movement thereof, said pilot valve including an atmospheric port, and means for opening said port when the said predetermined sub-atmospheric pressure is reached.
2. The combination of a vacuum pump, a

tank, and means for automatically unloading said pump when a predetermined pressure below atmospheric pressure has been reached in said tank including a movable valve actuating member enclosed in a casing and means whereby said member may be subjected on opposed sides to sub-atmospheric pressure.

3. In combination, a vacuum pump having valves for normally controlling flow of fluid therethrough, and control means for interrupting normal operation of said valves including a member movable to actuate one of said valves and subject on one side to sub-atmospheric pressure created by said pump and means whereby an opposed side of said member is adapted to be subjected to atmospheric and to sub-atmospheric pressure when the sub-atmospheric pressure created by said pump reaches different predetermined degrees.

4. The combination of a vacuum pump, and means for unloading the same when a predetermined pressure below atmospheric has been reached, including a valve actuating member operated by atmospheric pressure, and means whereby said member is subjected to atmospheric pressure only during the unloading operation.

5. In a vacuum producing system, a tank, a vacuum pump having its intake side connected with said tank, and means for interrupting the exhausting of air from said tank while its communication with the intake side of said pump is maintained including a valve actuating element and a pilot valve controlling the movement of said element and responsive to vacuum conditions in said tank.

6. In a vacuum producing system, a suction line, a vacuum pump having its intake connected with said suction line, and means for controlling the exhausting of air by said pump from said suction line while communication between said pump intake and said suction line is maintained including a valve actuating element constantly subjected on one side to suction line pressure and means for subjecting it alternatively on its other side to suction line or atmospheric pressure.

7. In combination, a vacuum pump having valve mechanism for normally controlling flow of fluid therethrough, and control means for unloading said compressor by means of said valve mechanism including a member directly subject on one side to sub-atmospheric pressure created by said pump, and means including a pilot valve whereby an opposed side of said member is adapted to be subjected to sub-atmospheric pressure when the sub-atmospheric pressure created by said pump reaches a predetermined degree.

8. In a vacuum producing system, a suction line, a vacuum pump having its intake connected with said suction line, and means for controlling the exhausting of air by said

- pump from said suction line while communication between said pump intake and said suction line is maintained including a valve actuating element constantly subjected on one side to suction line pressure and means 5 including a pilot valve responsive to suction line pressure for subjecting the opposite side of said element selectively to different pressures in accordance with variations in said suction line pressure.
- 10 9. In a vacuum producing system, a suction line, a vacuum pump having its intake connected with said suction line, and means for controlling the exhausting of air by said pump from said suction line while communication between said pump intake and said suction line is maintained including a valve actuating element constantly subjected on one side to suction line pressure and means 15 for subjecting it on its other side selectively to different pressures in accordance with variations in said suction line pressure.
- 20 10. Unloading means including a valve operating element, means for subjecting one side of said element constantly to the pressure conditions controlled by the unloading means, and means for subjecting the other side of said element selectively to said pressure conditions or to atmospheric pressure dependent upon variations in said pressure 25 conditions.
- 30

In testimony whereof I affix my signature.
